UNITED STATES PATENT OFFICE.

JOHN ASPIN, OF PRESTON, ENGLAND.

BRAKING MOTION FOR LOOMS FOR WEAVING.

Application filed October 22, 1923. Serial No. 670,117.

To all whom it may concern:

Be it known that I, JOHN ASPIN, a British subject, residing at Preston, county of Lancaster, England, have invented certain 5 new and useful Improvements in Braking Motions for Looms for Weaving, of which the following is a specification.

This invention relates to improvements in let off or weighting motions for the warp 10 beams of looms for weaving of the type in which the weight rope or chain at each end of the beam is attached to one end of a bell crank lever fulcrumed on the frame of the loom, the other ends of the bell crank lever 15 being connected together through a spring or springs which apply the desired tension on to the ends of the warp beam.

According to the present invention the 20 ends of the bell crank levers which are connected together through a spring or springs extend vertically upwards some distance above the beam and a spring or springs are connected to the end of one lever and to a chain, rod or the like connected to the end 25 of the other lever.

The invention will be described with reference to the accompanying drawings.

Fig. 1 is a view from the rear of a loom with the let off or weighting motion applied 30 thereto.

Fig. 2 is a view of a modified arrangement.

Fig. 3 is a detail view of lever forming the tension releasing motion.

Fig. 4 is a detail view showing construction of bell crank lever.

Fig. 5 is a detail view of modified adjustable bracket on which the bell crank lever may be fulcrumed.

Two bell crank levers A A¹ are pivoted one at each end of the frame either directly thereto or to an adjustable bracket B. The adjustable bracket B is made in two parts (see Fig. 5) the part b being affixed to the frame of the loom and the part b¹ sliding in relation to the part b. The part b is provided with a projecting bolt b² and the part b¹ with a slot b³ which slides over the bolt b².

By tightening up a nut on the bolt b² the part b¹ can be locked in any desired position. The part b¹ carries a stud b⁴ on which the bell crank lever is fulcrumed.

Each bell crank lever is as shown in Fig. 4 made in three parts, a vertical arm a extending above the beam C and two hori-

zontal arms a¹, a², a projection a³ on the arm a¹ engaging in an aperture a⁴ in the arm a². The arms a, a¹ and a² are locked together by a bolt a⁵ passing through them. The bell crank lever is fulcrumed at a⁶ on 60 the stud b⁴ of the adjustable bracket B or on a similar stud carried on the frame. The horizontal arms a¹, a² are provided with holes a⁷ to receive pins or screws carrying a hook d to which the ends of the weighting 65 chain D passing round the end of the warp beam C are attached.

The upper end of the vertical arm of the bell crank lever A carries a small lever E pivotally mounted thereon and held in the 70 position shown in Figs. 1 and 2 by a stop e of semi-cylindrical shape. A hook f is attached to a projection e¹ on the opposite end of the lever and to this hook is or are affixed one, two or more springs G the other 75 end of which is or are attached to a hook f¹ at the end of a chain F as shown in Fig. 1, or a bar F¹ as shown in Fig. 2. Where a chain F is employed the other end thereof is connected to a hook f² affixed to the top 80 of the vertical arm of the second bell crank lever A¹. When a rod F¹ is employed the end thereof is screwed and passes through a lug at the top of the vertical arm of the bell crank lever A¹ a nut in the form of a 85 handle wheel F² being employed to tighten up the bar.

The tension between the two bell crank levers A A¹ can be adjusted by shortening or lengthening the chains F or rod F¹ and 90 by varying the spring or springs G, springs of different size being employed as desired.

The lever E allows the tension on the warp beam to be readily removed by merely turning the lever upwards into or beyond 95 the vertical position.

The bell crank levers are provided with safety chains g connected to the frame of the loom so that should a spring G break from any cause the lever will not drop on 100 to the floor.

What I claim as my invention and desire to protect by Letters Patent is:—

1. In a warp beam weighting motion for looms for weaving the combination with the 105 chains passing around the ends of the beam, of two pivoted bell crank levers extending upwards above the beam, a tensioning spring connected to the upper end of one bell crank lever and a chain connected at one end to 110

the tensioning spring and at the other end to the upper end of the second bell crank lever.

2. In a warp beam weighting motion for looms for weaving the combination with the chains passing around the ends of the beam, of two pivoted bell crank levers extending upwards above the beam; a releasing lever pivoted to the upper end of one bell crank lever, a tensioning spring connected to the releasing lever and a chain connected at one end to the tensioning spring and at the other to the upper end of the second bell crank lever.
3. In a warp beam weighting motion for looms for weaving the combination with the chains passing around the ends of the beam, of two pivoted bell crank levers extending upwards above the beam, two adjustable brackets on each of which one bell crank lever is fulcrumed, a releasing lever pivoted to the upper end of one bell crank lever, a tensioning spring connected to the releasing lever and a chain connected at one end to

the tensioning spring and at the other to the upper end of the second bell crank lever.

4. In a warp beam weighting motion for looms for weaving the combination with each of the chains passing around the ends of the beam of two horizontal levers, a vertical lever carried between the horizontal levers forming a bell crank lever, an adjustable bracket on which said bell crank lever is pivoted, a releasing lever pivoted to the upper end of one bell crank lever, a tensioning spring connected to the releasing lever and a chain connected at one end to the tensioning spring and at the other to the upper end of the second bell crank lever.

In testimony whereof I have hereunto set my hand in presence of two subscribing witnesses.

JOHN ASPIN.
